CARTRIDGE LOADER

Elmer Lovell Smith, Longmeadow, and Carl E. Melhorn, Springfield, Mass., assignors to Package Machinery Company, Springfield, Mass., a corporation of Massachusetts

Application June 3, 1943, Serial No. 489,480

8 Claims. (Cl. 86—47)

This invention relates to a method of packaging a plurality of cartridges into pockets of a cardboard carton suitable for shipment to field stations or supply houses and the like.

The mechanism provided in this machine singles out cartridges from a hopper and places them one by one into individual pockets within a cardboard container. Improvements arise in the handling of said cartridges and the speed with which they are placed within said boxes for their quick delivery to the vital areas where needed. The handling of the cartridges and the delivery of the completely filled cardboard boxes onto the discharge conveyor of the machine for immediate delivery where needed will be clearly defined in the following description of the machine of which:

Fig. 1 is a right hand end view of the machine showing the box hopper mechanism and the general machine drive;

Fig. 2 is a front elevation of the machine with the exception of the box hopper mechanism which has been broken away;

Fig. 3 is a sectional view taken substantially along the line 3—3 of Fig. 2, showing the relation of the box conveyor to the receiving and transfer drums respectively;

Fig. 4 is a partial top plan taken just below the cartridge transfer drums substantially on the line 4—4 of Fig. 2 with parts omitted and broken away;

Fig. 5 is a sectional detail taken on line 5—5 of Fig. 4 to show one of the cartridge pusher chain units in relation to one of the cartridge transfer drums, with certain parts broken away;

Fig. 6 is a sectional detail taken substantially on the line 6—6 of Fig. 4 with parts broken away and showing one of the cartridge pusher drive mechanisms in relation to the transfer drum with parts omitted;

Fig. 7 is a form of modification showing means for adjusting the cartridge pusher chain if so desired;

Fig. 8 is a partial sectional view taken substantially along the line 8—8 of Fig. 4 showing the location and operation of the cartridge pusher at the last unit of the machine in relation to the last cartridge transfer drum with parts broken away;

Fig. 9 is a partial detail showing the relation of one of the cartridge pushers to one of the rotary pushers pushing the cartridges home into the several pockets of the cardboard boxes;

Fig. 10 is a detail looking at the lower portion of one of the cartridge transfer drums showing

the cartridge guides and the cartridges being delivered in proper alignment with the several pockets in the lower row of the cardboard boxes moving along in the background, the cartridge pusher and its operating mechanism being omitted for clearness;

Fig. 11 is a detail taken through one of the cardboard packing boxes showing one of the rotary pushers after having pushed the cartridges home in the upper row of the box;

Fig. 12 is a partial top plan taken along the same plane as Fig. 4 and joining the latter on line A—A;

Fig. 13 is taken substantially along the line 13—13 of Fig. 12 showing the drive, in detail, of the discharge paddles, and the relation of the box conveyor to the discharge belt;

Figs. 14, 15 and 16 are views showing the operation of the machine, Figs. 14 and 15 being taken as looking from the left of Fig. 16 showing the method of delivering the empty cardboard packing boxes onto the box conveyor while Fig. 16 is a rear view of the machine and shows the progress of the cartridges from the four delivery chutes to the receiving drums through the transfer drums and on into the boxes positioned on the conveyor chain.

Referring more particularly to the drawings it will be understood that the machine will comprise a suitable supporting frame generally indicated at 1. Mounted upon this main frame 1 are end frames 2 tied together by a cross piece member 3 which houses the supporting bearings for the overhanging cartridge drums on the right side looking in the direction of Fig. 3, and their respective drive mechanisms as seen on the left side in the same view. In front of end frames 2 and supporting the box hopper mechanism 4 is a U-shaped frame member 5 which is also supported by main frame 1.

The box hopper mechanism delivers empty boxes to the box conveyor to be filled with cartridges and finally pushed onto a discharge belt ready to be packed for shipment to the field stations or wherever needed. The box hopper consists of hopper sides 6 and back panel 7 supported by frame 8 mounted upon supporting frame member 5. The boxes to be filled are of cardboard and contain one longitudinal and nine cross partitions forming two rows of ten cartridge-receiving pockets. Along one horizontal edge of said box is hinged a flap portion large enough to retain the cartridges in the pockets in both rows when said flap is closed.

The operator places the empty boxes 10, just

described, in the hopper one above the other in a single pile (Fig. 1) with the flaps 11 toward the front and top. The lowermost box will rest on bottom support member 12 with the others on top of it. A pusher 13 reciprocates back and forth to push said boxes into the path of a reciprocating flapper 14 which pushes them down in front of the lugs on the continuously moving box conveyor 15 to be carried along through the machine.

The box hopper mechanism is driven from shaft 20 which rotates continuously. A crank 21 pinned to shaft 20 oscillates lever 22 mounted on stud shaft 23 by a link connection 24 to said lever. Pusher 13 is slidably mounted in ways 25 on frame member 5. Located between said ways is a slidable platform member 26 which supports member 27 and carries pusher 13 for oscillation in ways 25 previously mentioned (Fig. 1). Pusher 13 is oscillated back and forth by yieldably mounted lever 27' connected by a link 28 to a boss 29 formed on the under side of platform 26, said link 28 being pivotally secured to boss 29 by a pin 30. Lever 27', mounted on stud shaft 23, is yieldably secured to drive lever 22 by a spring 34 which is hooked between pin 35 on lever 22 and pin 36 on lever 27'. Lever 27' carries an adjusting screw 38 which is constantly forced against stop pad 39 on lever 22 by tension from said spring 34. The pusher 13 oscillates back and forth pushing one box after another to the box conveyor. Should anything happen so as to cause a box to jam or become lodged in the mechanism for any reason, lever 22 will follow the motion of crank 21 but lever 27' and pusher 13 may yield to avoid breakage. As soon as the obstruction is removed from the hopper mechanism spring 34 will cause set screw 38 to contact stop pad 39 as before and levers 22 and 27' will move in unison again to feed boxes to the conveyor. Any one of several well known detecting mechanisms may be employed to stop the machine in case of a gap in the supply of boxes or of an unavoidable accident with said box hopper mechanism. A cover 40 which encloses pusher 13 also acts as a back-stop to hold the boxes 10 as the pusher 13 returns from its forward position, as in Fig. 14, so that said pusher may pull itself out from under the lowermost box. As soon as the pusher 13 clears the box 10, said box will fall immediately onto the bottom member 12 of the hopper directly in the path of the pusher 13 as it advances on its next forward stroke (Fig. 15).

A bracket 42 mounted on hopper frame 8 carries side guides 43, one of which is shown in Fig. 1 as in the back. The front one has been removed for clearance. Centrally disposed between said side guides 43 and mounted for oscillation up and down in a swinging motion from pivot stud shaft 44 mounted in bracket 42, is a bell crank lever 45 which carries a flapper plate 14 to contact the box pushed under it by the pusher 13 and slap it down onto and in front of the oncoming lugs of the continuously moving box conveyor. The action of the pusher 13 and the flapper plate 14 is timed in perfect unison with the continuously moving lugs on the box conveyor so that each box is placed simultaneously between said lugs on said box conveyor. The front of the box, as seen traveling in the direction of the arrows in Fig. 16, contacts the lug pushing the preceding box and the back of the box is contacted by the lug pushing it, therefore positively guiding each box. The box conveyor is, in turn, in perfect timed relation with the four car-

tridge transfer drums so as to cause each pocket in each box to be positively aligned with its respective pocket in the continuously rotating cartridge transfer drums so that as the conveyor travels with the boxes and the transfer drums continuously rotate and deliver the cartridges, all the pockets in all the boxes will be filled with cartridges, the method for which will be explained more fully later in the description.

10 The flapper plate 14 moves continuously to slap one box down onto the conveyor after another. To accomplish this, bell crank 45 is connected by a link 46 to a lever 47 pivotally mounted at 48 to frame 5 in back of box hopper 4. Lever 47 carries a roll 49 which is held in contact with cam 50 by tension of spring 51. Cam 50 is securely fastened to hopper drive shaft 20 which rotates continuously in the direction of the arrow (Fig. 1). As the box is pushed under the flapper when said flapper is in its upraised position indicated by dotted lines (Fig. 14) it will be held momentarily between side guides 43, supported from frame 42 (Fig. 1), until plate 14 contacts the top of said box and pushes it down toward the box conveyor traveling along underneath. The box will be guided further by radially shaped guides 53 and 54 respectively. The flap 11 will strike against the rounded portion 55 of hopper bottom member 12, which also comprises guide portion 53, and cause said flap to be bent upwardly as the box is pushed down onto the box conveyor as seen in Fig. 15. With the flap raised in this position, access to the several pockets in the box will be unobstructed when the cartridges are fed from the transfer drums into said pockets. The flaps are retained in this uplifted position during the boxes' travel through the machine by a guide member 56 (Fig. 16). Said flap guide 56 will be cut away, at the four cartridge supplying stations (Fig. 4) enough to allow the entrance of the cartridges into said pockets in said boxes and for the free action of the rotating pusher which will be described later.

45 The box conveyor carries empty boxes from the box hopper, along past the four cartridge loading stations where the boxes are filled simultaneously with cartridges and finally delivers them onto the discharge conveyor which will be explained later. The box conveyor is made up of box-carrying lugs 58 interconnected by links 59 to form a continuous conveyor chain 15 (Fig. 16). Box carrying lugs 58 have extensions 60 on each side which ride in ways 61 formed in support bracket 62 mounted on frame 1. Box retaining and pushing lugs 63 are formed out of lugs 58 and are centrally disposed between the box conveyor bottom plates 64 secured to the top of bracket 62 and spaced apart as seen in Fig. 1 so as to receive box retaining and pushing lugs 63 as they move continuously with the boxes through the machine. Side guide 54 associates with guide 53 to form a channel at the box hopper station by which the boxes will be guided transversely as they are carried along on the conveyor chain.

50 Box conveyor chain 15 travels over an idler sprocket 68 supported by bracket 69 which in turn is mounted on frame 1 (Fig. 1). A guard 70 encloses sprocket 68 and conveyor chain 15 as the conveyor support bracket 62 does also along the entire length of the machine. At the discharge end of the machine (Fig. 13) is located the conveyor chain drive sprocket 71 which is pinned to conveyor drive shaft 72 for continuous operation.

Box guide 54 at the box hopper station is replaced by guide 65 (Fig. 3) which gives support to the lower corner of the boxes after said boxes leave said box hopper station and are placed securely between the conveyor lugs 63 on the box conveyor to be filled with cartridges and delivered onto the discharge conveyor, which will be described later. Box flap guide 56 (Fig. 3) replaces guide 53 (Fig. 1) at the box hopper station, to form a continuous channel when associated with bottom plates 64 and lower box corner guide 65 secured to plate 64 through which said boxes are pushed. Several brackets are mounted successively along the length of conveyor support bracket 62, one of which is shown in Fig. 3 as at 75. Through these several brackets 75 passes a shaft 76 which carries, at different intervals, brackets 77, one of which is also shown securely mounted upon shaft 76 to be readily pivoted with said shaft by the movement of handle 78 also secured to shaft 76 for the inspection of boxes as they travel along on the conveyor 15. Secured to bracket 77 is a box corner guide member 79 in the form of an angle iron. Also secured to bracket 77 is a box hold-down and flap guide member combined as shown at 80. When bracket 77 is in its proper position as in Fig. 3 box hold-down member 80 and flap guide member 56 will together form a channel as seen in Fig. 3 for box flap 11 to be positively guided in its bent-up position during its travel through the machine so the cartridge may be easily placed within the several pockets in said boxes.

For delivering cartridges to the cardboard boxes this machine has four cartridge chutes, the construction of which is similar to machines built before and will not be described in detail. The several chutes are filled by any suitable automatic means so as to deliver a constant flow of cartridges to the receiving drums for their transfer into the transfer drums and hence into the several pockets of the cardboard boxes for shipment. Detecting mechanisms may be employed in the several chutes for the automatic stopping of the machine, should a gap occur in the cartridge supply in any one chute. Cartridge guides 85 which make up said chutes are disposed vertically above the center of cartridge receiving drums (Fig. 16).

For delivery of the cartridges from the chutes 85 the machine consists of four cartridge receiving drums mounted centrally and vertically above four cartridge transfer drums (Fig. 16). The semi-circular pockets in said transfer drums coordinate with the pockets in the cardboard boxes being carried along on the box conveyor as both move continuously while the cartridges are being delivered from the former to the latter. The method of delivering said cartridges from one to the other will be described later.

The uninterrupted flow of cartridges fall by their own weight through said chutes 85 into the several semi-circular elongated pockets which are disposed radially around the periphery of the receiving drums 90, 91, 92 and 93 respectively, said drums being mounted for continuous rotation on shafts 94, 95, 96 and 97 respectively (Fig. 16). Said shafts are journaled in bearings in cross member 3 and carry on their opposite ends gears 98, 99, 100 and 101 respectively (Figs. 2 and 3). Secured to said spur gears 98, 99, 100 and 101 are respective bevel gears 102, 103, 104 and 105 which are continuously driven by bevel gears 106, 107, 108 and 109 severally mounted on continuously rotating drive shaft 110 which is journaled

in bearings 111 mounted on upright frame members 2 supported from base 1, previously described.

Cartridge transfer drums 112, 113, 114 and 115 also contain semi-circular shaped pockets disposed radially around their peripheries for the purpose of receiving the several cartridges from the previously mentioned receiving drums and are centrally mounted below said cartridge receiving drums and are severally supported on shafts 116, 117, 118 and 119, also journaled in cross member 3 (Fig. 3). Spur gears 120, 121, 122, and 123, pinned to shafts 116, 117, 118, and 119 respectively are driven constantly by spur gears 15 98, 99, 100, and 101 previously mentioned as driving the four receiving drums.

Therefore the cartridge receiving and transfer drums are driven in a 2 to 1 ratio from drive shaft 110 through said beveled gears mentioned 20 previously, said transfer drums being constantly rotated in a speed equal to that of the box conveyor for the transfer of cartridges from the radially disposed pockets on the periphery of the transfer drums into the several pockets of the 25 cardboard packing boxes held firmly between the lugs on the box conveyor and finally delivered onto the discharge conveyor with said cartridges in the several pockets within said cardboard boxes which will be more fully explained later.

30 The cartridges fall from their respective chutes 85 into the several pockets 125 in the receiving drums 90, 91, 92, and 93 respectively. They are guided from lateral movement while in these several pockets by S-shaped guides 125' at their base 35 ends which are towards cross member 3, and removable guides 126 at their tip ends. Guides 126 also possess a circumferential guiding portion as at 127 (Fig. 16) to retain the cartridges in their respective pockets 125 until said pockets 40 communicate with corresponding pockets 128 in the periphery of the transfer drums disposed directly below.

The cartridges in certain pockets in the receiving drums, said pockets being designated by numbers 1 to 10 (Fig. 16), will always fall into correspondingly numbered pockets in the transfer drums. The transfer drums will have two sets of said numbers 1 to 10 (Fig. 16) because of their half speed as compared to the speed of the receiving drums. Namely, as the cartridge in pocket number 7 in receiving drum 90 rides off the circumferential guide portion 127 of tip-end guide member 126 (Fig. 16) it will fall into corresponding number 7 pocket in transfer drum 112, directly below, as they both rotate continuously in the direction of the arrows.

Looking at transfer drum 112 for example, numbers 1, 2, 3, 4, 5, 6, and 7 respectively represent cartridges in these aforesaid numbered pockets 60 as having been transferred into these several pockets from correspondingly numbered pockets 1, 2, 3, 4, 5, 6, and 7 in receiving drum 90, cartridge number 7 being the last one to have been transferred into drum 112 according to the position here shown. Cartridges numbered 8, 9 and 10 are retained in their several pockets in drum 90 but will eventually fall into correspondingly numbered pockets 8, 9 and 10 in transfer drum 112. Therefore, pockets numbered 6, 5, 4, 3 and 70 2 in receiving drum 90 are now empty and the several cartridges that were in these pockets have been transferred into pockets 6, 5, 4, 3, 2 and also number 1 in transfer drum 112. Pocket number 1 in receiving drum 90 now has another cartridge in it which it has just received from 75

the supply chute 85. As the drum 90 turns continuously, the following pockets 2, 3, 4, 5, etc., around the periphery of the drum will also be filled again and as they travel down the other side of the circumferential arc in the direction of the arrow they will be guided and held into their respective pockets until they ride off the circumferential guiding surface 127 into their correspondingly numbered pockets in the receiving drums.

Pockets 125 in all the receiving drums are rounded on their leading edges according to the direction of the arrow as at 130 so that more time will be gained for the entrance of the cartridges into said pockets 125 from the cartridge guides 85 while the receiving drums rotate continuously. Pockets 125 in all the receiving drums are noticeably deeper than pockets 128 in the transfer drums. Said pockets 128 are purposely made shallow so as to enable the cartridge pushers to contact the lower edges of the base ends of the cartridges and push them out of said pockets 128 in the transfer drums into corresponding pockets in the cardboard packing boxes carried on the box conveyor, which will be more fully explained later in the description. It will be noticed that two blank spaces numbered 11 occur on the periphery of drum 112 and one is also present on drum 90. After a cartridge has fallen into pocket 10 in receiving drum 90 for example, the cartridge immediately following in the delivery chute 85 (first unit, Fig. 16) will have ridden onto the blank, arcuated surface 11 of said drum 90 and thence into pocket numbered 1 here shown on the drawings in this particular position of the machine. Blank arcuated surface 11 on receiving drum 90 will always register with the two correspondingly arcuated surfaces also numbered 11 on said transfer drum 112 as both drums rotate continuously.

Said cartridge handling mechanism just described will be recognized on the drawings as the first typical unit in a series of four as shown in Fig. 16. The other three units operate correspondingly and all are so timed to each other that each pocket in said receiving drums will communicate with the same corresponding pocket in the transfer drums during every cycle of their operation and said pockets in each transfer drum have a specific pocket to communicate with in the cardboard packing boxes for the accurate delivery of the cartridges from the transfer drums into said pockets in the packing boxes with the aid of a single cartridge pusher and also a rotary pusher for each unit, the action of which will now be explained.

Looking at the partial plan view of the cartridge pushing units, Fig. 4, it will be noted that there are four such units each comprising a cartridge pusher and a rotary pusher operating simultaneously. The cartridge pusher pushes the cartridges out of the pockets in the transfer drum into the several pockets in the cardboard packing boxes as far as its construction will permit. Said cartridges are further pushed home to their proper position, entirely within said pockets in said cardboard boxes, by a rotary pusher acting in conjunction with said cartridge pusher and both operate continuously to deposit said cartridges into the several pockets in the packing boxes as said boxes are carried along on the box conveyor. Each pocket in each cardboard box will contain a cartridge when said box leaves the last transferring unit during its travel with the box

conveyor and will then be delivered, fully packed, onto the discharge conveyor of the machine.

The cartridge pushing unit comprises two parallel mounted endless chains 135 each being carried upon three sprockets (Figs. 5 and 6), one of which is a double driving sprocket 136 mounted on and driven from shaft 137. Said shaft 137 is continuously rotated by bevel gear 139 which meshes with continuously rotating bevel gear 138' 10 suitably secured to constantly rotating shaft 173 (Fig. 2). Said sprockets and driving shaft 137 are mounted in suitable bearings between the two sides of an H-shaped bracket 140. Said bracket 140 comprises an extension 141 from each side frame, said extensions being secured by bolts 142 to the under side of main frame 1 through aperture 143 in said main frame as best shown in Figs. 4, 5, 6, and 8 respectively. Mounted across said parallel chains 135 are cross pieces 145 suitably secured so as to carry cartridge pushers 146, centrally mounted upon said cross pieces 145 so as to travel between top enclosure pieces 147 mounted along the top of bracket 140 and spaced apart as at 148 to allow the passage of 20 said cartridge pushers 146. Multiple cartridge pushers 146, only two of which are shown for clearness, are carried on said parallel chains 135 spaced apart from each other along said chains at proper intervals to contact the lowermost 30 edges of the base ends of the cartridges (Fig. 8) as they are brought one after the other into the path of said approaching pushers 146 by the continuous rotation of transfer drums 112, 113, 114, and 115 in the direction of the arrows previously 35 described, and the continuous advancing of said cartridge pushers 146 on chains 135 as they travel around their triangular shaped course as shown best in Fig. 6. Top enclosure pieces 147 mounted on upright sides of bracket 140 are 40 both made more rigid and the cartridge pusher mechanism is further enclosed by front end plate 148 secured to H-shaped bracket side members at their front ends by bolts 149. The chains 135 supporting said cartridge pushers 146 ride up 45 onto chain supporting shoes 150 which lie under the chain rollers so as to give rigid support to said pushers as they contact cartridges in the pocket 128 of the several transfer drums and push said cartridges into the pockets of the cardboard packing boxes.

A slot S may be provided in bracket 140 to receive the squared end of an adjustable member T upon which is mounted one set of sprockets over which cartridge pusher chains 135 pass.

55 At the center of a U-shaped extension of member T is provided a bolt and lock nut arrangement which bears against end plate 148. Chains 135 may be tightened or loosened by said bolt and lock nut so as to keep cartridge pushers 146 in 60 proper alignment and for easy assembly of said cartridge pushers and their chains respectively. Each of the four cartridge pusher units shown in Fig. 4 may be provided with this adjustable feature here shown in Fig. 7 as a modified form.

65 The cartridge pushers are all traveling transversely to the direction of travel of the cardboard packing boxes on conveyor 15 as seen best in Fig. 4. The entire cartridge pushing unit is mounted in an aperture in the main frame 1 at an angle sufficient to cause pushers 146 to push cartridges progressively from the pockets 128 of the transfer drums as said drums rotate continuously. The location of transfer drum 112 in relation to said cartridge pusher, rotary pusher, 70 box flap guide 56, and cardboard box conveyor 75

15, is best shown in Fig. 4 in dot-dash lines on the drawings. Although the cartridge pushers 146 travel transversal to the direction of travel of the box conveyor 15 said pushers are constructed so that the pushing surface 155 of each pusher is parallel at all times to the direction of travel of said box conveyor 15 and therefore said pushing surface will push flat against the base ends of the cartridges (Figs. 4, 8, and 9) as it contacts them to push them from their pockets 128 in the transfer drums into the several pockets in the cardboard packing boxes traveling along on the box conveyor 15.

Referring to Fig. 10, we have a full scale view (Figs. 4, 5, 6, 8) with certain parts broken away to show how the several parts are assembled so as to guide the cartridges from their several pockets in the transfer drum 112 to their corresponding pockets in the cardboard packing box. In this view we are looking at the inside front face of the transfer drum just inside the S-shaped cartridge guide 125'. It is a view showing the operation at the first cartridge transfer unit in Fig. 16 but looking in the opposite direction from said Fig. 16 with the packing boxes traveling along in the background.

Circumferential guides 157 and 158 (Figs. 4 and 10) confine the cartridges to their pockets 128 during their travel, in the direction of the arrow in Fig. 16, from the receiving drum pockets to the several pockets in the cardboard packing boxes. The lower portions of S-shaped guides 125' serve to guide the cartridges at their base ends from lateral travel toward the supporting cross member 3 of the machine (Fig. 3). Circumferential guide 157 is provided with a beveled surface 159 for guiding the cartridges against a lateral movement toward the box conveyor and packing boxes. The shoulder 159' of the cartridges guides against this beveled surface 159 while said cartridges are positioned in the pockets 128 of the transfer drums and are lowered in their arcuated travel onto the milled-out circumferential surface 160 on lower cartridge guide 161 (Figs. 3, 4 and 10) secured to the top surface of aforesaid enclosure pieces 141 (Fig. 4).

Here, said cartridges lie free from guides 157 and 158 for their traverse journey into the pockets of the cardboard packing boxes (Figs. 8 and 10). Said cartridges are still guided longitudinally by their contact with the lower edges of the pockets 128 in the transfer drum. Said transfer drum is continually rotating and by said contact with said lower edges of said pockets 128, carry said cartridges along in the direction of and parallel to, the box conveyor while the cartridge pusher travels in a traverse direction toward said box conveyor and the face of said cartridge pusher contacts the base end of said cartridge and pushes it along out of said transfer drum pocket 128 into corresponding pockets or cells in the lowermost row of the cardboard packing box on conveyor 15. Because of the cartridge pushers being mounted on a continuously moving endless chain 135 they are not able to push said cartridges home into the pockets of the cardboard packing boxes but leave said cartridges in a position shown in dotted lines C' in Figs. 4 and 9, and in full lines C' in Fig. 6. Cartridges left in this position by said pushers are continuously carried along in their respective pockets by the continuously advancing box conveyor 15 earlier described. As said cartridges advance with the box conveyor, they are severally contacted simultaneously by a rotary pusher 165 operating con-

tinuously in a circumferential motion, the path of which is indicated by dot-dash lines 166 in Fig. 9, to contact said cartridge base ends and push them circumferentially traversal to their longitudinal direction of travel, thereby forcing them home simultaneously into their respective pockets in the cardboard packing box. Aforesaid box flap guide 56 is shown cut away to allow the aforesaid action of the cartridge pushers and 10 said rotary pushers and will now keep the properly positioned cartridges C² within their respective pockets. Rotary pushers 165 are so constructed (Fig. 11) to contact upper and lower rows of cartridges simultaneously whenever said rotary pusher pushes home a group of cartridges, whether said pusher is definitely operating on the lower or upper row of cartridges at the time. Therefore, rotary pushers 165 see to it that all cartridges are within their several pockets at 20 each transfer unit as the box conveyor carries them along and past the opening in said box flap guide 56.

The continuous motion of said rotary pusher is circumferential in the direction of the arrow 25 Fig. 9. To accomplish this, said rotary pusher is mounted on two cranks, one of which is driven. Mounted for rotation in front bearing 170, suitably secured to main frame 1, is a shaft 171 continuously driven by bevel gears 172 from drive shaft 173, the continuous drive for which will be explained later. Pinned to the top of shaft 30 171 is a rotary pusher crank member 173 which comprises crank pin 174 and crank link pin 175 positioned radially from said pin 174 to form a supplemental crank portion 176 for the operation of crank link member 177. Mounted on crank pin 174 is the extreme end of rotary pusher arm 178. Rotary pusher arm 178 also comprises an additional bearing mounted on corresponding 35 crank pin 174' carried on an idler rotary pusher crank unit mounted in rear bearing 180 also on main frame 1. Said idler rotary pusher crank unit mounted in bearing 180 is identical to driven crank unit mounted in front bearing 170. Therefore, as driven shaft 171 rotates in a counter-clockwise direction, rotary pusher 165 will rotate in a circumferential path as shown at 166, Fig. 9, due to the construction of double cranks 173 and 40 173' mounted in aforesaid bearings 170 and 180 respectively, as just described.

It will be noted that the packing box consists of two rows of pockets separated longitudinally by a transverse partition centrally supported by multiple vertical partitions spaced apart to form 45 said pockets or cells within said box. This machine is designed to first fill the lower row of said box with cartridges and then the upper row in the same manner, as will be seen in Figs. 8, 10, and 16, and will now be described.

As aforesaid, the cartridges fall from the chutes 85 into pockets 125 in the receiving drums and are transferred from said pockets into corresponding pockets 128 in the transfer drums. Looking at Fig. 16, packing box B¹ now contains 60 cartridges in the lower row designated by numbers 1, 2, 3, 4, and 5 respectively, said cartridges having been transferred from pockets 128 in transfer drum 112 correspondingly numbered 1, 2, 3, 4, and 5 respectively, when said pockets were 65 in alignment with each other just as pockets 128 numbered 6 and 7 now are in this particular aligned position, a full scale view of which is shown in Fig. 10 for illustrating more clearly the possibility of said pockets 128 in said transfer 70 drum being in perfect alignment during a short 75

interval within the cycle of operation of the machine.

The cartridge pusher contacts the base end of the cartridge when said drum and box pockets are aligned as shown by number 7 cartridge in Fig. 10 and while the drum continues to rotate, in the direction of the arrow, the cartridge pusher 146 pushes said number 7 cartridge out of its pocket 128 into corresponding pocket number 7 in the cardboard box container shown going along in back on conveyor 15, not shown in this view but previously explained. Cartridge drum 112 will travel from the position shown by number 7 cartridge (Fig. 10) to number 6 cartridge position which is approximately one inch, during which time said cartridge pusher will have pushed said cartridge number 7 approximately three inches on a traversal path through the transfer drum pocket 128 containing said number 7 cartridge. The same operation occurs simultaneously for each cartridge in each pocket of the transfer drums, said operation to be followed up immediately by the aforesaid action of the rotary pusher to place said cartridges home fully within the packing box pockets.

It should be noted in Figs. 16 and 10 that each drum provides cartridges for filling alternate pockets successively in said cardboard packing boxes. By the cooperation and accurate timing of the following drum, which also fills alternate pockets left empty by the first-named drum, the lowermost row of pockets in the packing box will first be completely filled with cartridges, the near completion of which is here shown in box B², Fig. 16. Namely, cartridge transfer drums 112 and 113 supply cartridges to be placed in the lowermost row of pockets in the cardboard packing boxes while immediately afterward, drums 114 and 115 simultaneously provide cartridges for filling the uppermost row of pockets in the same aforesaid cardboard packing boxes for their delivery onto the discharge conveyor, to be explained later.

Referring to Fig. 16, numbers 6, 7, 8, 9, and 10 in box B³ represent where cartridges with corresponding numbers 8, 9, and 10 now being retained in pockets 128 of transfer drum 112 by circumferential guides 157 and 158 respectively and by S-shaped guide 125' are going to be placed. Number 6 cartridge is already as far into its box pocket as pusher 146 can push it, and the following pusher 146 on cartridge pusher chains 135 previously explained is now acting on cartridge number 7 to push it within its pocket in box B³ during the time said cartridge and pockets are traveling to the position shown by number 6 cartridge.

Referring to the first cartridge transfer unit, namely receiving drum 90 and transfer drum 112, it will be noticed on the drawings, Fig. 16, that if said transfer drum 112 skips the first lower row pocket designated by X in cardboard packing box B¹, the very first pocket designated by Y will be filled in the following box B³. Because of the box alignment with said transfer drum in this particular position shown, the last pocket will be filled with cartridge numbered 5 in the lowermost row of box B¹ and due to the regular spacing of pockets 128 around the periphery of drum 112, cartridge numbered 6 in said transfer drum will enter said first pocket Y in the lowermost row in box B³. The box conveyor pushing chain lug 63 cooperates with the peripheral space between said pockets 128 carrying cartridges numbered 5 and 6 respectively and said lowermost

row of pockets are alternately filled as previously described. Following along in this same manner, cartridge numbered 10 will be placed in the next to the last pocket in the lower row of box B³.

5 Therefore, peripheral blank space numbered 11 on transfer drum 112 will cooperate with vacant pocket Z in box B³ and conveyor chain lug 63 and the first corresponding pocket in the lower row of the box immediately following which can 10 be referred to corresponding pocket X in box B¹ here shown so as to cause alternate lower row pockets to be filled in said following box in the same order as the pockets in box B¹ were filled previous to filling box B³ pockets.

15 A complete cycle of box pocket filling has now been described for the lower row of pockets in the cardboard packing box and the same identical construction and operation occurs for filling the uppermost row in the same packing boxes with 20 cartridges except that to enable the radial pockets 128 on transfer drums 114 and 115 to cooperate with said upper row of pockets in the cardboard packing boxes, supporting drive shafts 118 and 119 for said transfer drums 114 and 115 25 respectively are positioned higher in alignment than aforesaid driving shafts 116 and 117 for said transfer drums 112 and 113 (Figs. 2 and 16).

By referring to the third cartridge transfer unit, namely that consisting of receiving drum 30 92 and transfer drum 114 operating to fill the uppermost row of pockets in said cardboard packing boxes, the occurrence and operation of peripheral blank surface numbered 11 on said transfer drums is clearly shown as previously 35 described. Alternate pockets numbered 1, 2, 3, 4 and 5 respectively in the uppermost row of box B⁴ will be filled from transfer drum 114 and the remaining empty pockets left by said drum 114 will be supplied with cartridges from correspondingly numbered pockets 6, 7, 8, 9, and 10 respectively 40 from said transfer drum 115 which acts in conjunction with said drum 114 to fill said upper rows in said cardboard packing boxes with cartridges, previously described.

45 To sum up the aforesaid operations required to fill all available pockets in each cardboard packing box with cartridges as said box travels continuously on box conveyor 15 past four continuously operating simultaneous cartridge transfer

50 units, the action taken is as follows. First transfer drum 112 will furnish cartridges to fill alternate pockets 1, 2, 3, 4, and 5 respectively as shown placed in box B¹ and alternate pockets 6, 7, 8, 9, and 10 respectively as shown being filled in box 55 B³ (Fig. 16). The next box immediately following B³, not shown, will have pockets filled in the order similar to box B¹. Therefore cartridge transfer drum 113 will furnish necessary cartridges to fill empty pockets left in the lowermost

60 row in boxes B¹ and B³ respectively, first filling in pockets numbered 6, 7, 8, 9, and 10 respectively as shown after having been filled accordingly in box B⁴, and 1, 2, 3, 4, and 5 respectively in lower row of B² as here shown in the act of completely 65 filling said vacant pockets in said lower row of said box B². The same procedure takes place in filling the upper row of pockets in the same boxes. Box B⁵ shows cartridges 6, 7, 8, 9, and 10 respectively in the uppermost row placed within their

70 correspondingly alternate pockets, said cartridges being furnished by transfer drum 114, while box B⁴ is shown about to receive cartridges numbered 1, 2, 3, 4, and 5 in correspondingly numbered pockets 1, 2, 3, 4, and 5 respectively. 75 Box B², immediately following box B⁴ will have

said pockets in the uppermost row filled according to the same arrangement as box B⁵ did, namely pockets numbered 6, 7, 8, 9, and 10 respectively. Cartridge transfer drum 115 is so constructed and timed with relation to drum 114 that it will fill all remaining empty pockets left in the uppermost row of the packing box by transfer drum 114. Namely, in box B⁵, pockets numbered 6, 7, 8, 9, and 10 respectively in the uppermost row are now being completely filled from transfer drum 115, as shown on the drawings Fig. 16, and peripheral blank member 11 on transfer drum 115 will bridge across pockets numbered 5 in the upper row in box B⁶ and corresponding pocket numbered 6 in the upper row in box B⁵ previously filled by drum 114 and previously described, so that cartridges numbered 1, 2, 3, 4, and 5 now being retained in drum 115 by guides 157 and 158 respectively will be deposited in the upper row of box B⁵ directly above correspondingly numbered cartridges 1, 2, 3, 4, 5 respectively, already in place in the lower row of said box. Box B⁷ shows all twenty cartridges being represented by their respective numbers placed in proper order to completely fill said cardboard packing box for delivery onto the discharge conveyor.

The bottom portion of said cardboard boxes has been removed in Fig. 16 to show the available cartridge pockets and the transverse longitudinal partition separating each longitudinal row of ten cartridges, one above the other. Box flaps 11 are also shown in their raised position during their entire travel past cartridge receiving drums 112, 113, 114, and 115 respectively as previously described, and held in this aforesaid raised position by member 80 cooperating with flap guide member 56 (Fig. 3) to form a retaining channel for said box flaps 11 to travel through, also described previously.

During the process of filling the uppermost row of the cardboard packing boxes with cartridges, it is very important to guide the cartridges with greater care and accuracy than was required for filling the lowermost row. The object is to carry the center of the tip end of the cartridge well above the transverse longitudinal partition where there are already present cartridges filling all pockets which have been placed there previous to filling said upper row. To accomplish this, lower guide member 161, Fig. 8, is purposely milled deeper on its forward surface 185 and gradually rises to form an inclined surface 186 upon which all upper row cartridges are released from transfer drums 114 and 115 respectively, for their transverse travel into the upper row of pockets within the cardboard boxes. There are two such lower guide members 161, one each of which is secured to members 147 atop the two last cartridge pusher units positioned directly below the two last cartridge transfer drums 114 and 115 respectively. A flat upper surface 187 (Figs. 4 and 8), positioned beyond said inclined surface 186 and also slightly above the level of said transverse longitudinal partition within said cardboard box, serves to level off said cartridges high above said transverse partition safely within said upper row of pockets in said packing boxes as said cartridges are pushed simultaneously into said boxes by cartridge pushers 146 previously described and shown in Fig. 8.

Upon completion of filling all of said pockets in each cardboard packing box as said box is moved along on conveyor 15, said conveyor carries said completely filled packing box to the discharge

mechanism for the purpose of righting said box and delivering it out of the machine for further packing into containers which are finally sent to field stations or ammunition supply houses or wherever desired. It will be noticed by the drawings that all of said packing boxes have been laying on their sides with the box flaps 11 held in an upright position for the easy entrance of all of the cartridges into the several pockets within said boxes, during their entire continuous travel with the box conveyor 15 from the time they were severally placed upon said conveyor from out of the previously mentioned box hopper station, starting the beginning of their continuous travel through said machine, to where they are now approaching, namely the discharge station. It is the purpose of the discharge mechanism to remove said completely filled cardboard boxes, containing twenty cartridges, from the continuously moving box conveyor 15 and place said boxes in an upright position onto a discharge conveyor for their safe delivery out of said machine.

To accomplish this aforesaid purpose of said discharge mechanism, it is necessary for the pushing surface of the discharge paddles 190 to move continuously in a plane parallel to the continuously moving box conveyor 15. Said discharge mechanism is supported from bracket 195 mounted on main frame 1 (Fig. 13). Rigidly secured to bracket 195 is stationary gear 196 around which three sets of planetary gears are carried for rotation on stub shafts 197 and 198 respectively. Said stub shafts are severally mounted in bearings on disk member 199 which in turn is pinned at 200 to continuously rotating vertical discharge paddle drive shaft 201 supported in bearings 202 on support bracket 195 simultaneously driven by bevel gear 203 pinned to the lower end of said shaft 201. Said bevel gear 203 is driven by bevel gear 204 which is suitably secured to aforesaid box conveyor drive sprocket 71 pinned to aforesaid continuously rotating box conveyor drive shaft 72 for continuous operation of the discharge paddles 190. As the planetary gears 205 travel around the periphery of stationary gear 196, with the teeth of said gears in mesh, stub shafts 197 with gears 205 rotate in a counter-clockwise direction. Said gears 205 mesh with larger gears 206 supported on stub shafts 198 also journaled in bearings on disk member 199 and cause said gears 206 to travel in a clockwise direction just fast enough in accordance with the speed of rotation of shaft 201 to cause discharge paddles 190, which are made part of said gears 206, to move continuously in a parallel path equal to the direction of travel of the box conveyor.

By this parallel movement of the discharge paddles 190, said paddles are brought flatly against the upper portion of the open top of the cardboard packing box, containing twenty cartridges, as it lies on its side between the box conveyor lugs 63 which have conveyed it from the aforementioned box hopper station to said discharge station. Because of the fact that stub shafts 198 are mounted on disk member 199, which rotates continuously in a counter-clockwise direction, said shafts travel in a circumferential path around drive shaft 201. Because of the planetary gearing used to drive discharge paddles 190, previously described, said paddles travel in a circumferentially parallel path to the box conveyor therefore squarely forcing said car-

tridge filled cardboard box out from between the conveyor lugs 63 of box conveyor 15, over the rounded portion 210 of previously described conveyor support bracket 62, which runs the entire length of the machine.

The cartridge filled box will first be eased onto the discharge belt 212 in a leaning position as shown in Fig. 13 in full lines, and as said discharge belt travels in the direction of the arrow in Fig. 12, the cartridge filled cardboard box will be cammed into an upright position as shown by dotted lines in Fig. 13 by the diminishing width between the conveyor side guides as shown at 211 of surface 210, as the box is carried along out of the machine on said discharge belt 212. A box guide 213 is provided opposite the line of action during the actual pushing of said cartridge filled box out from between the box conveyor lugs 63 and onto the discharge belt 212 as previously explained so as to confine said box to said discharge conveyor. Said discharge belt 212 slides over member 213 which in turn supports the weight of the filled cartridge boxes and said belt is driven from flanged pulley 214. Said pulley 214 mounted on a shaft in bearings supported from frame 1 in turn supports a sprocket 215 which is driven by a chain 216 from a sprocket on a continuously rotating discharge belt drive shaft 217.

To continuously rotate the numerous drive shafts previously mentioned throughout the description of this machine a motor 220 is provided (Fig. 1). A drive pulley 221 secured to said motor drive shaft 222, continuously drives pulley 223 mounted upon a shaft 224 journaled in bearings 225 which are suitably secured at the extreme end of main frame 1 as viewed in the direction of Fig. 1. Secured to said shaft 224 is a gear 226 which drives gear 227 supported for continuous rotation upon shaft 228 also supported in bearings 229 at the end of frame 1. Mounted in bearings projecting from main frame 1, Figs. 1 and 2, is shaft 173 continuously driven by gear 174 which meshes with gear 227, previously mentioned. Therefore, rotary pushers 165 are continuously driven through bevel gears 172 previously described as mounted on shaft 173 for continuous operation.

Also suitably secured to shaft 228 at the furthest end of main frame 1 is a sprocket 230 which drives shaft 110 by a chain 111 and sprocket 112 suitably secured to said shaft 110, thereby providing continuous rotation for all cartridge drums as previously explained. On the extreme end of shaft 110, opposite to sprocket 112, Fig. 2, is secured another sprocket 233 by which box hopper drive shaft 20 is continuously driven. Shaft 20 is coupled by gearing 235 to stub shaft 236 mounted within box hopper support frame 5, said shaft 236 being continuously rotated by a chain 237 driven from sprocket 233. Said chain 237 drives sprocket 238 suitably secured to said stub shaft 236, thereby providing continuous driving means for the previously described box hopper mechanism. Mounted upon continuously rotating shaft 228 is a worm gear 240 which drives worm wheel 241 which is secured to box conveyor drive shaft 72 thereby providing continuous drive to said shaft 72 for the continuous movement of box conveyor 15 as previously described. Each cartridge pusher unit possesses a bevel driving gear 138 previously described as being mounted for driving shaft 137 to cause said cartridge pushers 146 to travel continuously. Said gears 138 of each cartridge

pusher unit mesh with corresponding bevel gears 138' which are pinned to shaft 173 for the continuous operation of all cartridge pusher units.

What we claim is:

5. 1. A loading mechanism for placing cartridges in cell-type containers, comprising a continuously rotating transfer drum provided with axially extending cartridge-receiving recesses, a continuously moving conveyor having container pushers advancing containers past the transfer drum at the same surface speed as the recesses and with a cell in alignment with each recess, and a pusher engaging the base of a cartridge in one of the recesses and having a diagonal direction of motion the longitudinal component of which is the same as the longitudinal speed of the conveyor and movable to shift a cartridge from a pocket to a cell of the container.
- 10 2. A loading mechanism for placing cartridges in cell-type containers, comprising a continuously rotating transfer drum provided with axially extending cartridge-receiving recesses, a continuously moving conveyor having container pushers advancing containers past the transfer drum at the same surface speed as the recesses and with a cell in alignment with each recess, a pusher engaging the base of a cartridge in one of the recesses and having a diagonal direction of motion the longitudinal component of which is the same as the longitudinal speed of the conveyor and movable to shift a cartridge from a pocket to a cell of the container.
- 15 3. A loading mechanism for placing cartridges in cell-type containers, comprising a continuously rotating transfer drum provided with axially extending cartridge-receiving recesses, a continuously moving conveyor having container pushers advancing containers past the transfer drum at the same surface speed as the recesses and with a cell in alignment with each recess, a pusher engaging the base of a cartridge in one of the recesses and having a diagonal direction of motion the longitudinal component of which is the same as the longitudinal speed of the conveyor and movable to shift a cartridge from a pocket to a cell of the container, and a second pusher trailing in an endless path tangential to the containers and adapted to engage a cartridge partially seated in a cell and completely transfer it into the cell.
- 20 4. A loading mechanism for placing cartridges in cell-type containers comprising a pair of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with alternate cells in alignment with successive recesses, the spacing of the axes of the drums being such that the recesses of the second drum are in alignment with the cells missed by the recesses of the first drum, and a pusher engaging the base of a cartridge in one of the recesses and having a diagonal direction of motion the longitudinal component of motion of which is the same as the longitudinal speed of the conveyor and movable to shift a cartridge from a pocket to the cell of the container.
- 25 5. A loading mechanism for placing cartridges in cell-type containers comprising a pair of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with alternate cells in alignment with successive recesses, the spacing of the axes of the drums being such that the recesses of the second drum are in alignment with the cells missed by the recesses of the first drum, and a pusher engaging the base of a cartridge in one of the recesses and having a diagonal direction of motion the longitudinal component of motion of which is the same as the longitudinal speed of the conveyor and movable to shift a cartridge from a pocket to the cell of the container.
- 30 6. A loading mechanism for placing cartridges in cell-type containers comprising a pair of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with alternate cells in alignment with successive recesses, the spacing of the axes of the drums being such that the recesses of the second drum are in alignment with the cells missed by the recesses of the first drum, and a pusher engaging the base of a cartridge in one of the recesses and having a diagonal direction of motion the longitudinal component of motion of which is the same as the longitudinal speed of the conveyor and movable to shift a cartridge from a pocket to the cell of the container.
- 35 7. A loading mechanism for placing cartridges in cell-type containers comprising a pair of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with alternate cells in alignment with successive recesses, the spacing of the axes of the drums being such that the recesses of the second drum are in alignment with the cells missed by the recesses of the first drum, a pusher engaging the base of a cartridge in one of the recesses and having a diagonal direction of motion the longitudinal component of motion of which is the same as the longitudinal speed of the conveyor and movable to shift a cartridge from a pocket to the cell of the container.
- 40 8. A loading mechanism for placing cartridges in cell-type containers comprising a pair of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with alternate cells in alignment with successive recesses, the spacing of the axes of the drums being such that the recesses of the second drum are in alignment with the cells missed by the recesses of the first drum, and a pusher engaging the base of a cartridge in one of the recesses and having a diagonal direction of motion the longitudinal component of motion of which is the same as the longitudinal speed of the conveyor and movable to shift a cartridge from a pocket to the cell of the container.
- 45 9. A loading mechanism for placing cartridges in cell-type containers comprising a pair of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with alternate cells in alignment with successive recesses, the spacing of the axes of the drums being such that the recesses of the second drum are in alignment with the cells missed by the recesses of the first drum, and a pusher engaging the base of a cartridge in one of the recesses and having a diagonal direction of motion the longitudinal component of motion of which is the same as the longitudinal speed of the conveyor and movable to shift a cartridge from a pocket to the cell of the container.
- 50 10. A loading mechanism for placing cartridges in cell-type containers comprising a pair of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with alternate cells in alignment with successive recesses, the spacing of the axes of the drums being such that the recesses of the second drum are in alignment with the cells missed by the recesses of the first drum, and a pusher engaging the base of a cartridge in one of the recesses and having a diagonal direction of motion the longitudinal component of motion of which is the same as the longitudinal speed of the conveyor and movable to shift a cartridge from a pocket to the cell of the container.
- 55 11. A loading mechanism for placing cartridges in cell-type containers comprising a pair of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with alternate cells in alignment with successive recesses, the spacing of the axes of the drums being such that the recesses of the second drum are in alignment with the cells missed by the recesses of the first drum, and a pusher engaging the base of a cartridge in one of the recesses and having a diagonal direction of motion the longitudinal component of motion of which is the same as the longitudinal speed of the conveyor and movable to shift a cartridge from a pocket to the cell of the container.
- 60 12. A loading mechanism for placing cartridges in cell-type containers comprising a pair of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with alternate cells in alignment with successive recesses, the spacing of the axes of the drums being such that the recesses of the second drum are in alignment with the cells missed by the recesses of the first drum, and a pusher engaging the base of a cartridge in one of the recesses and having a diagonal direction of motion the longitudinal component of motion of which is the same as the longitudinal speed of the conveyor and movable to shift a cartridge from a pocket to the cell of the container.
- 65 13. A loading mechanism for placing cartridges in cell-type containers comprising a pair of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with alternate cells in alignment with successive recesses, the spacing of the axes of the drums being such that the recesses of the second drum are in alignment with the cells missed by the recesses of the first drum, and a pusher engaging the base of a cartridge in one of the recesses and having a diagonal direction of motion the longitudinal component of motion of which is the same as the longitudinal speed of the conveyor and movable to shift a cartridge from a pocket to the cell of the container.
- 70 14. A loading mechanism for placing cartridges in cell-type containers comprising a pair of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with alternate cells in alignment with successive recesses, the spacing of the axes of the drums being such that the recesses of the second drum are in alignment with the cells missed by the recesses of the first drum, and a pusher engaging the base of a cartridge in one of the recesses and having a diagonal direction of motion the longitudinal component of motion of which is the same as the longitudinal speed of the conveyor and movable to shift a cartridge from a pocket to the cell of the container.
- 75 15. A loading mechanism for placing cartridges in cell-type containers comprising a pair of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with alternate cells in alignment with successive recesses, the spacing of the axes of the drums being such that the recesses of the second drum are in alignment with the cells missed by the recesses of the first drum, and a pusher engaging the base of a cartridge in one of the recesses and having a diagonal direction of motion the longitudinal component of motion of which is the same as the longitudinal speed of the conveyor and movable to shift a cartridge from a pocket to the cell of the container.

the longitudinal speed of the conveyor and movable to shift a cartridge from a pocket to the cell of the container, and a second pusher traveling in an endless path tangential to the containers and adapted to engage a cartridge partially seated in a cell and completely transfer it into the cell.

5. A loading mechanism for placing cartridges in cell-type containers comprising a pair of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with alternate cells in alignment with successive recesses, the spacing of the axes of the drums being such that the recesses of the second drum are in alignment with the cells missed by the recesses of the first drum, the recesses being arranged in groups of a number equal to that of the number of cells in a complete layer, but with a space between the groups sufficient to bridge the gap between the last and first cells to be filled in adjacent pairs of boxes, and a pusher engaging the base of a cartridge in one of the recesses and having a diagonal direction of motion the longitudinal component of motion of which is the same as the longitudinal speed of the conveyor and movable to shift a cartridge from a pocket to the cell of the container.

6. A loading mechanism for placing cartridges in double row cell-type containers comprising a plurality of sets of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with the cells of the two rows aligned with the re-

cesses of the two sets respectively, and means at each drum for transferring the cartridges from the recesses to the cells.

7. A loading mechanism for placing cartridges in double row cell-type containers comprising a plurality of sets of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with the cells of the two rows aligned with the recesses of the two sets respectively, means at each drum for transferring the cartridges from the recesses to the cells comprising a pusher engaging the base of a cartridge in one of the recesses and having a diagonal direction of motion the longitudinal component of motion of which is the same as the longitudinal speed of the conveyor and a second pusher traveling in an endless path tangential to the containers and adapted to engage a cartridge partially seated in a cell and completely transfer it into the cell.
- 10 15 20 25 30 35
8. A loading mechanism for placing cartridges in double row cell-type containers comprising a plurality of sets of continuously rotating transfer drums each provided with spaced, axially-extending cartridge-receiving recesses arranged circumferentially of the drum, a continuously moving conveyor having container pushers advancing containers past the transfer drums at the same surface speed as the recesses and with the cells of the two rows aligned with the recesses of the two sets respectively, means at each drum for transferring the cartridges from the recesses to the cells, and guide means for the cartridges of the second row directing them into the cells of the second row well away from the partition dividing the two rows of cells.

ELMER LOVELL SMITH.
CARL E. MELHORN.

CERTIFICATE OF CORRECTION.

Patent No. 2,339,299.

January 18, 1944.

ELMER LOVELL SMITH, ET AL.

It is hereby certified that error appears in the printed specification of the above numbered patent requiring correction as follows: Page 2, first column, line 57, for the word "clearance" read --clearness--; and second column, line 38, for "a" before "guide" read --flap--; page 4, first column, line 65, for "a" before "far" read --as--; and that the said Letters Patent should be read with this correction therein that the same may conform to the record of the case in the Patent Office.

Signed and sealed this 28th day of March, A. D. 1944.

(Seal)

Leslie Frazer
Acting Commissioner of Patents.
